ELECTRIC WATER-HEATER.

1,252,661.

Specification of Letters Patent.

Patented Jan. 8, 1918.

Application filed May 23, 1917. Serial No. 170,839.

To all whom it may concern:

Be it known that I, HOWARD K. CLOVER, a citizen of the United States, residing at Los Angeles, in the county of Los Angeles and State of California, have invented new and useful Improvements in Electric Water-Heaters, of which the following is a specification.

This invention relates to electric water heaters and it has for its object to provide an improved electric water heater whereby a stream or jet of water may be heated as it passes through and issues from the heater. In the preferred embodiment of the invention, a faucet-like body having valve means to control the flow of fluid therethrough and an internal resistance element is provided; in accordance with the invention the resistance element which is disposed in the water passage in the faucet body may be removed for replacement and repair, together with other electrical features, by properly manipulating the valve-controlling stem whereby adjustment of the valve to control the flow of liquid is made; and furthermore the valve *per se* may remain on its seat to prevent the flow of fluid while the valve stem and resistance element are disconnected or removed. In the form of the invention shown in the drawing the valve means is shown as a rotatable cock having its operating stem detachably secured thereto as by a bayonet joint, the resistance element being shown as disposed in the faucet body and surrounding the valve operating stem and in position to be removed when the stem is detached from the cock. To this end, the resistance element is supported by or mounted on a water passage closure at the top of the faucet and above the discharge opening thereof, the valve-operating stem being provided with a nut or wrench portion whereby the closure may be unscrewed from the body portion after detachment of the valve-operating stem from the cock. An electrical controlling switch to control the flow of electrical energy through the resistance element is mounted preferably at the closure and is removable therewith, the switch blade or blades being connected with the valve-operating stem so that upon rotation of such stem by means of a hand wheel or the like the plug cock will first be moved to "open" position to permit the flow of fluid, ordinarily supplied under pressure to the device, and

then the switch blade or blades will be caused to contact with fixed contacts of the switch whereupon the resistance element will be energized and the flowing liquid heated as it passes over such resistance element. After the desired quantity of liquid so heated has been discharged by the heater the hand wheel may be further turned in its proper direction of rotation to first cause the breaking of the circuit by moving the switch blade or blades and then upon continued rotation of the hand wheel move the cock or plug thereof to "closed" position, thus shutting off the further flow of fluid. A suitable switch casing surmounts the faucet-like body so that a "sealed-in" or moisture-proof switch box is had. A coil compression spring is preferably arranged between the switch box cover and the hand wheel to draw the valve-operating stem outwardly and maintain the same in assemblage with the cock or plug at the bayonet joint thereof.

A further object of the invention is to provide a device of the character disclosed which will be relatively simple and inexpensive in construction and organization when its features of superiority such as its adaptability to varying working conditions and facility in disassembling for purposes of repair are considered.

With the above and other objects in view, the invention consists in the novel and useful provision, formation, combination, and relative arrangement of parts, members and features, all as hereinafter described, shown in the drawing, and finally pointed out in claims.

In the drawing:

Figure 1 is a central vertical sectional view of an electric water heater constructed and organized in accordance with the invention; and

Fig. 2 is a horizontal sectional view taken on the line $\alpha-\alpha'$, Fig. 1, and looking in the direction of the appended arrows.

Corresponding parts in both the figures are designated by the same reference characters.

Referring with particularity to the drawing, in the embodiment of the invention therein shown, A designates a faucet casing, B designates valve means therein, C designates valve-operating means, D designates electrical heating means, E designates switch

means to control the supply of electrical energy to the heating means D, and F designates means for supplying electrical energy.

5 The casing A is shown as comprising a tubular body portion 3 and a discharge spout 4 near one end thereof. The tubular body portion is provided near one end with a valve seat 5 beneath which the same is internally threaded as at 6 to receive a pipe or nipple 7 leading from any suitable source of fluid supply. At its end opposite the valve seat 5 the tubular body 3 is internally threaded as at 8 to receive a closure 9 which closure is threaded as at 9^a for engagement with the threaded portion 8 of the body 3 and comprises a switch casing provided with an annular channel 10 at its base 10^a, which channel 10 defines a boss 10^b.

10 The valve means B is shown as a rotatable conical one way plug cock 12 seated against the valve seat 5 and provided with an internal fluid passage 13, which passage extends from the lower end of the plug 12 to a point at one side of said plug 12 as at 14 so that communication may be established between the fluid supply pipe 7 which is threaded into the body 3 and through a bushing 15 and the hollow interior of the body 3, a duct 16 being provided in the valve seat 5 to that end.

15 The valve-operating means C preferably comprises a rotatable valve stem 17, and a hand wheel or the like 18 secured thereto and externally of the body 3. The valve stem 17 at its lower end is provided with a lateral lug or projection 19 which is adapted to take into an angled slot 20 provided in the upper end of the plug 12 such plug 12 being bored 25 at its upper end to receive the lug-carrying end of the valve-operating stem 17. The angled slot extends longitudinally of the plug from the upper end thereof as at 20^a, then transversely or circumferentially of the plug as at 20^b and then upwardly a short distance as at 20^c so that a bayonet joint as between the plug 12 and the valve-operating stem 17 is provided. The switch casing 9 is preferably annular in form and has a removable cover 12^a between which cover and the hand wheel a compression spring 21 is interposed. This compression spring 21 by drawing upwardly or outwardly on the valve-operating stem maintains the stem 17 and plug 12 in assemblage so that upon rotation of the hand wheel the plug will be rotated to permit the discharge of fluid from the device or shut off such discharge of fluid. The closure 9 is bored as at 9^a to accommodate the stem 17 and a packing 9^b is provided in an enlargement of the bore 9^a to prevent the invasion of the switch box by fluid from the interior of the body or to prevent the escape of such fluid. Just below the packing 20 the bore 9^a is squared as at 9^c so that a nut

25 or wrench portion 17^a provided on the stem 17 may be caused to engage the closure 9 after detachment of the valve-operating stem 17 and the plug 12 so that by first permitting upward movement of the hand wheel 18 under the influence of the spring 21 or by manually raising such hand wheel, the closure may be unscrewed upon rotation of the hand wheel, it being understood that the nut portion 17^a by entering the squared portion 9^c of the bore 9^a will engage the closure 9.

30 The electrical heating means D is shown as comprising a coil 22 of resistance wire which is secured to binding posts 9^d and 9^e passing through the closure 9 and is supported thereby, insulation bushings 23 being provided, from which point of support the ends of the element are connected through the switch box forming the closure 9, one to a suitable contact 24 in the switch box and the other out of the switch box for connection with a circuit wire f of the electrical supply means F. The other circuit wire f' of the supply means F is connected with another contact 25 within the switch box 9. These contacts 24 and 25 are included within the switch means E, which means E preferably comprises in addition thereto a curved connection bar 26 yieldingly rotatably mounted in connection with the stem 17 by suitable mechanism 27 which may be of standard form such as is ordinarily employed in or incorporated in a "snap switch" of the Trumbull type, all as will be readily understood by those skilled in the art. The fixed switch points 24 and 25 are so arranged in the casing 9 that the flow of electrical energy through the switch bar 26 and consequently through the resistance element or coil 22 is permitted only after sufficient rotation of the hand wheel to open the plug cock and permit the flow of fluid through the body 3 and over the resistance coil 22 disposed therein. After the desired amount of heated fluid has been discharged 110 through the heater a slight further rotation of the hand wheel will cause the switch bar 26 to leave the points 24 and 25, thus interrupting the supply of electrical energy to the resistance coil and permitting the flow of 115 cold fluid until the continued rotation of the hand wheel, through rotation of the plug 12, shuts off the supply of fluid altogether. It will be understood that each succeeding demand for heated fluid is to be met by 120 merely rotating the hand wheel as just described. If it is desired to discharge only cold fluid through the heater the hand wheel may be rotated to assume the position required to discharge cold fluid and need not 125 be rotated far enough to bring the switch bar 26 across the points 24 and 25. An insulation lining 28 may be provided internally of the body 3 to prevent contact of the resistance coil 22 therewith.

To replace or repair the resistance coil or switch features all that is necessary is to press downwardly or inwardly on the rotatable hand grip or wheel 18 so that the lug of the bayonet joint may be moved downwardly and then rotated through the hand wheel to bring such lug into the portion 20 of the slot 20 in the plug 12 whereupon the valve-operating stem 17 with its lug 19 may be raised, either by the spring 21 or manually to bring the nut portion 17^a into engagement with the closure 9 whereupon such closure or switch casing may be unscrewed from the body portion 3 and upon removal 15 of the closure or switch casing the resistance coil 22 and the switch box and attendant features may be lifted clear of the casing 3 with the valve-operating stem 17. The device may be again assembled after replacement or repair of the resistance element or other features by again replacing the closure or switch casing 9 and by opposite rotation of the hand wheel 18 to thread the closure 9 into place in the body 3. After the closure 25 9 has been so threaded into place the hand wheel may be depressed or moved against its spring 21 to cause the lug 19 on the stem 17 to again enter the slot 20 and engage the plug 12 after which engagement the spring 30 21 will maintain the hand wheel in extended position so that the plug may be rotated upon rotation of the hand wheel and stem 17.

A suitable supporting base may be provided for the body 3, such base being shown 35 as a supporting flange 29 secured to the body 3 by means of a set screw 30.

Access may be had to the interior of the switch casing by removing the cover 12^a, after first removing the hand wheel 18 and 40 the spring 21.

The switch being of the type known as a "snap switch", the lag of the switch before making or breaking the circuit may be utilized to insure the supply, first of fluid 45 to be heated, and then the supply of electrical energy, and the cutting off of the electrical energy, and then the cutting off of the fluid, thus preventing the heating of the resistance element while no fluid is flowing 50 over the same.

Having thus disclosed my invention, I claim and desire to secure by Letters Patent:

1. In an electric heater, a casing having a discharge opening, a valve to control the flow of fluid through said casing, means for operating said valve, electric heating means in said casing, and means to control the supply of electrical energy to said heating means; said heating means being adapted 55 for inter-engagement with said valve operating means whereby said heating means may be removed from the casing upon removal of the valve operating means therefrom.

2. In an electric heater, a casing having a

discharge opening, a valve to control the flow of fluid through said casing, means for operating said valve, electric heating means in said casing, and means to control the supply of electrical energy to said heating 70 means; said heating means being adapted for inter-engagement with said valve operating means whereby said heating means may be removed from the casing upon removal of the valve operating means therefrom; there being means whereby said valve operating means and said valve may be detachably inter-engaged to permit the removal of said valve operating means from the casing separately from said valve. 75

3. In a heater for fluids, a casing adapted to permit the passage of fluid therethrough and having a discharge opening, a valve seated in the casing at one end thereof, a rotatable valve-operating stem, an electrical 85 resistance element in said casing and in position to be traversed by fluid, means for supplying electrical energy to said resistance element, and controlling means for the electrical energy so supplied; said resistance 90 element being removable with said valve-operating stem.

4. In a heater for fluids, a casing adapted to permit the passage of fluid therethrough and having a discharge opening, a valve 95 seated in the casing at one end thereof, a rotatable valve-operating stem, an electrical resistance element in said casing and in position to be traversed by fluid, means for supplying electrical energy to said resistance 100 element, and controlling means for the electrical energy so supplied; said resistance element and said controlling means in part being removable with said stem.

5. In a heater for fluids, a casing adapted 105 to permit the passage of fluid therethrough and having a discharge opening, a valve seated in the casing at one end thereof, a rotatable valve-operating stem, an electrical resistance element in said casing and in position to be traversed by fluid, means for supplying electrical energy to said resistance 110 element, and controlling means for the electrical energy so supplied; said resistance element and said controlling means in part 115 being removable with said stem; there being quick detachable means whereby said valve stem and said valve may be inter-engaged.

6. In a heater for fluids, a casing adapted 120 to permit the passage of fluid therethrough, a rotatable valve seated in said casing, a valve stem extending through said casing and provided externally thereof with operating means, an electrical resistance element in said casing and in position to be traversed by fluid, means for supplying electrical energy to said resistance element, means for controlling the supply of electrical energy to said resistance element, and means for supporting said resistance element in position. 125

tion in said casing; said valve stem being provided with means adapted to be engaged with said resistance element supporting means and said stem being provided with means whereby said valve may be detachably engaged by said stem; there being yielding means whereby said detachable means are held in engagement.

In testimony whereof, I have signed my name to this specification in the presence of 10 two subscribing witnesses.

HOWARD K. CLOVER.
